TYPEWRITING MACHINE

Otto E. Gathmann, Syracuse, N. Y., assignor to
 L. C. Smith & Corona Typewriters, Inc.,
 Syracuse, N. Y., a corporation of New York

Application July 19, 1940, Serial No. 346,315

16 Claims. (Cl. 197—179)

The invention relates to improvements in typewriting machines, and more particularly to the tabulating mechanism of such machines.

The principal object of the invention is to provide in a typewriting or like machine an improved tabulating mechanism of the key-set type which is of simple, inexpensive and sturdy construction.

Another object is to provide, in a key-set tabulating mechanism having a settable and unsettable column stop for each letter space position of the platen carriage of the machine, an improved construction and assembly of the stop carrying bar and stops.

A further object of the invention is to improve key-set tabulating mechanism such as that disclosed in U. S. Patent No. 2,099,011, issued November 16, 1937, to Carl Gabrielson et al., and in the co-pending application of Laurence B. Hill, Serial No. 342,863, filed June 28, 1940.

To the foregoing and other ends which will hereinafter appear, the invention consists of the improved devices, features of construction, and arrangements and combinations of parts and devices hereinafter particularly described and particularly pointed out in the appended claims.

In the accompanying drawing illustrating the preferred embodiment of the invention,

Fig. 1 is a fragmentary vertical longitudinal sectional view of the improved machine taken on the line 1—1 of Fig. 2;

Fig. 2 is a fragmentary transverse sectional view of the machine taken approximately on the line 2—2 of Fig. 1, certain parts being broken away for clarity of illustration of the stop setting and unsetting means;

Fig. 3 is a fragmentary top plan view partly in section approximately on the line 3—3 of Fig. 1;

Figs. 4 and 5 are detail sectional views similar to Fig. 1 illustrating, respectively, the setting of a selected column stop individually in operative position, and the unsetting of a selected set column stop individually into inoperative or cleared position;

Fig. 6 is a detail view showing how any column stop may be detached from and attached to the column stop bar and the column stop pivot wire;

Fig. 7 is a detail sectional view on the line 7—7 of Fig. 2;

Fig. 8 is a detail sectional view on the line 8—8 of Fig. 2; and

Figs. 9 to 11 are detail views showing a slightly modified construction, Fig. 9 being a fragmentary front view of the modified stop and stop bar assembly, Fig. 10 a top view thereof, and Fig. 11 a detail perspective view showing one of the 53

groups of three column stops engaged in each slot of the stop bar in the modified construction.

The invention has been shown embodied in an L. C. Smith typewriting machine having a tabulating mechanism constructed as shown in the prior patent and more particularly in the co-pending application above referred to, except as said mechanism is modified by the present improvements. Only so much of the known machine as is necessary for a clear understanding of the present invention has been shown and will be described.

The platen carriage 10 of the machine has the usual roller platen 11 journaled therein and is mounted as usual on the main framework 12 of the machine to travel back and forth transversely of the machine, and is letter-spaced from right to left under control of the usual carriage escapement mechanism (not shown). The carriage 10 is releasable from control of the carriage escapement mechanism by the usual escapement-releasing or carriage-releasing mechanism (not shown) for tabulating jump or running movement of the carriage from right to left in the known manner. Fixedly held to the carriage adjacent opposite ends of the carriage are two brackets 13 which rigidly support the opposite ends of a column stop carrying bar 14 which extends horizontally transversely of the machine, said stop bar being fixedly held at each of its ends to the adjacent bracket 13 by a screw 15.

The column stop carrying bar 14 is of oblong cross-section and is held to the brackets 13 with its two wider faces disposed in superposed horizontal planes. This bar according to the present invention is slotted inward from top to bottom thereof along both its front and rear edges at greater than letter-space intervals to provide a row of column stop guiding and spacing slots 16 along the front edge of the bar and a similarly spaced row of column stop guiding and spacing slots 17 of like number along the rear edge of the bar. Each slot 16 is directly opposite a different one of the slots 17 and the slots of each row are similarly spaced apart greater than letter space intervals with the same spacing for the slots of both rows and with each slot 16 directly opposed to a slot 17.

Settable column stops 18 of novel construction, one for each letter-space position of the carriage, are rockably mounted on the stop bar 14, certain of the stops 18 being omitted from the drawing for clarity of illustration. These novel stops have a novel mounting means including the stop carrying bar 14 and coact with

their novel mounting means to detachably hold themselves to the mounting means and to arrest and detain each stop in either set or unset position relatively to the bar.

The stops 18 are pivotally held to a straight pivot wire 19 which is laterally insertible in and removable from a groove 20 of V-shape in cross-section which extends longitudinally of the stop bar 14 and is formed in the front vertical face of the bar. The depth of groove 20 transversely of the bar 14 is substantially less than that of slots 16.

The stops 18 are adapted to hold the pivot wire 19 in the groove 20 as hereinafter explained, and each stop 18 is of substantially C-shape in side elevation and consists of a single piece of sheet metal. The stops are so formed as to be readily stamped in quantity by inexpensive dies from a thin sheet of metal, and are formed of thin sheet metal which is slightly resilient or springy, and each stop is so formed as to be resiliently expansible and contractible edgewise of the stop. The stops 18 are adapted as hereinafter described to hold themselves and the pivot wire 19 assembled with the stop-carrying means for positively limited pivotal setting and unsetting movements of the stops about the pivot wire 19 and to prevent accidental disconnection of any stop 18 and of the pivot wire 19 from the stop bar 14, while permitting ready assembly of the wire and stops with the bar and disassembly of the stops and wire from the bar, and permitting individual detachment and attachment of any stop 18 from and to the wire and the remainder of the stop-carrying means.

Each stop 18 is formed adjacent one of its ends with a pivot bearing in the form of a slot 18^a which is open at one end. The slot 18^a is wide enough for passage of wire 19 through the open end of the slot to the closed end of the slot, and the open end of said slot 18^a faces approximately toward the opposite or free end of the C-shaped stop 18. Each stop is formed at its outer edge with two integral projections or lugs 22 and 23 spaced apart along the stop and extending outwardly substantially radially to the pivotal axis of the stop. At its inner edge each stop 18 is formed with two integral projections or lugs 24 and 25 extending inwardly substantially toward the pivotal axis of the stop, projection 25 being formed at the free end of the stop. Between projections 24 and 25 and close to projection 25, each stop 18 is formed at its inner edge with a stop-latching projection or cam-hump 28 which projects inwardly a lesser distance than projections 24 and 25.

A flat metal latching and retaining bar 100 for all of the column stops 18 is held flatwise against the under face of the stop-carrying bar 14 by clamping screws 101 threaded into the bar 14. Bar 100 is preferably provided with slots 102 extending transversely of the bar, and the shanks of the screws 101 extend through these slots to permit bar 100 to be clamped to bar 14 in different fore and aft adjusted positions of the bar 100 with the rear edge of bar 100 protruding rearward slightly beyond the root ends or foremost ends of the slots 17, but not to the rear or open ends of slots 17, as shown. The rear edge of bar 100 is preferably rounded as shown more clearly in Fig. 6. Bar 100 extends longitudinally of bar 14 past all stops of the set of column stops 18 and the cam hump 28 of each stop 18 is adapted to snap above and below said edge to releasably lock the stop in

unset and set positions respectively. Projection 25 of each stop 18 is adapted to engage under said bar 100 to arrest unsetting movement of the stop.

5 All set stops 18 are simultaneously unsettable by a universal unsetting device comprising a rock shaft 31 and a fin 32 on said shaft. Shaft 31 is of circular cross-section having reduced coaxial bearing end portions 31^a to the outer end of one of which is removably fixed at 33 a forwardly extending operating rock arm 36 formed with a key or finger-piece 37, said arm and key being located at the right-hand side of the carriage outwardly beyond the adjacent bracket 13. Between its reduced bearing end portions 31^a the rock shaft 31 is formed with the integral flat fin 32 which projects rearwardly from the shaft and extends past all of the stops 18 and normally lies flatwise against the top face of bar 14. Fin 32 is substantially tangential to the periphery of the main part of the rock shaft 31, and said shaft and its fin overlies the top face of the unslotted medial portion of the bar 14.

25 To detachably and rockably hold the rock shaft 31 to the bar 14, a pair of sheet metal bearing brackets 103 are detachably held to the top face of bar 14 by screws 104. Each bracket has a pair of integral upstanding forwardly extending hook-shaped arms 105 hooked over the adjacent reduced bearing end portion 31^a of shaft 31 to hold the main portion of said shaft rockably to and against the top face of bar 14 with fin 32 underlying the projections 24 of the several column stops, which projections are engageable with the top face of the fin to positively arrest setting movement of stops 18. The innermost arms 105 of the brackets 103 abut the ends of the main portion of shaft 31 to hold the shaft against axial movement.

To restore and normally yieldingly hold the universal stop unsetters 31-32 in the normal position thereof above described and shown in the drawing, there is provided a self-holding 45 but readily detachable return spring 106 which, like the column stops, is stamped of substantially C-shape from resilient sheet metal for edgewise resilient expansion and contraction of the spring transversely of the shaft 31 and bar 14. This C-shaped spring 106 has an open-ended pivot slot 106^a in one end thereof similar to the slot 18^a in each of the column stops 18 for detachable pivotal engagement of the spring 106 with the stop pivot wire 19. The stop bar 14 is provided 55 with a slot 16^a (Fig. 7) similar to slots 16 for receiving and guiding the pivoted slotted end of spring 106. The spring 106 is arched over the shaft 31 and its free end is engaged with and yieldingly presses constantly against shaft 31 and fin 32 above the fin substantially at the juncture of the fin with said shaft.

The spacing of the projections 24, 25 and 28 of each stop 18 is such, as shown, that upon rocking of any stop 18 from its unset position of Figs. 1, 2, 3 and 5 to its set position of Fig. 4, the latching projection 28 will be forced down past the rear edge of bar 100 and engage under the latter as projection 24 engages the top face of fin 32 of the universal unsetters 31-32 to positively arrest the setting movement of the stop 18. Upon rocking of any stop 18 from its set position to its unset position, the cam hump 28 will be forced upward past the rear edge of bar 100 and engage over the latter as projection 25 engages the under face of the bar 100 adjacent the rear

edge of bar 100 to positively arrest unsetting movement of the stop 18.

It will also be obvious that, by pressing down on the finger-piece 37, the fin 32 of the universal unsetter 31-32 may be rocked upward and forward to unset all stops 18 which may be set at the time of depression of the finger-piece, said fin in this operation thrusting against the projection 24 of any set stop to move the stop to unset position. The universal unsetter 31-32 is similar to that disclosed in the co-pending application above referred to.

Each stop 18 is arched over the bar 14 and the universal unsetter 31-32, and projections 22 and 23 of each stop extend generally rearwardly from the downwardly extending rear portion of each C-shaped stop 18 for coaction with an individual stop setter and unsetter 41-43 by means of which stops 18 may be individually set and unset selectively. This individual stop-setting and unsetting means is only partly shown and described herein as it is the same as that disclosed in the prior patent above referred to.

Said last-mentioned means comprises the individual stop-setter and unsetter 41-43 rockable by key-applied force either to the position shown in Fig. 4 or to the position shown in Fig. 5 from the normal idle intermediate position of said setter and unsetter shown in Figs. 1, 2 and 3, and automatically returned to said last-mentioned position from either of the first two mentioned positions upon release of the key-applied force. This setter and unsetter 41-43 comprises a yoke 41 having its two legs pivoted at their rear ends on a fixed pin 42, one leg of said yoke being formed with a stop-setting and unsetting finger 43. Pin 42 extends horizontally transversely of the machine and is fixed in the main frame 12 of the machine above and behind the stop bar 14.

The key-controlled means for so shifting the stop-setter and unsetter 41-43 from, and restoring it to, idle position includes a vertically reciprocable link 45 connected at 44 to the right-hand leg of yoke 41, and a vertically reciprocable link 53 connected to link 45 by a cross-pin or cross-rod 54 rigid with both links. Shifting of the rigid link device 45-53-54 upward by key-applied force from a normal position thereof to which it is automatically restored upon release of key force rocks the stop-setter and unsetter from normal position to that of Fig. 5 to unset a single set stop 18 aligned with the finger 43, the finger thrusting against projection 22 of said stop to unset the stop. Shifting of the link device downward by key-applied force from its normal idle position to which it is restored upon release of the applied key force rocks the stop-setter and unsetter from its normal idle position to that of Fig. 4 to set a single stop 18 aligned with finger 43, the finger thrusting against projection 23 of the stop to set the stop. Restoration of the rigid link device 45-53-54 to normal position restores the stop-setter and unsetter 41-43 to normal position.

The finger 43 of the device 41-43, which swings the stops individually about their pivotal axis to set or unset a single selected stop at a time, extends forwardly from the yoke 41 and is located substantially in the medial vertical longitudinal plane of the machine. The thickness of finger 43 transversely of the machine is substantially equal to that of each column stop 18 and in each letter-space position of travel of the carriage a different one of the stops 18 is located in the same vertical fore-and-aft plane through

the machine in which the finger 43 lies. The finger 43 normally projects in between the projections 22 and 23 of any stop 18 aligned therewith. The spacing apart of the two projections 22 and 23 of each stop 18 is such that during travel of the carriage, while the stop-setter and unsetter 41-43 is in idle or neutral position, the projections 22 of all stops 18 will pass above the finger 43 and the projections 23 of all stops 18 will pass below finger 43 whether the stops be set or unset. The spacing apart of the projections 22 and 23 of each stop 18 is also such that, when said stop is registered with finger 43, downward swinging of the finger from idle position will set that stop by thrust of the finger on projection 23 and upward swinging of the finger from idle position will unset the stop by thrust of the finger against projection 22, but return movement of the finger to idle position will not shift the stop.

The projections 23 of the column stops 18 also serve as abutment elements of said stops for coaction with a suitable settable counterstop 86 on the machine frame in tabulating operations. The counterstop 86 shown, and the means for setting it, in the improved machine, correspond to those disclosed in the prior patent above mentioned. This counterstop 86 is located substantially midway between the sides of the machine and is guided at its upper end adjacent the stop bar 14 in a fore-and-aft extending slot 87 in a part of the main frame 12. Suitable key-controlled means, as set out in said prior patent, are provided for releasing the carriage for a tabulating jump from right to left and for shifting the counterstop 86 from a normal idle position of said stop shown in Figs. 1 and 2 to an active position of said stop 86 shown in Fig. 4.

When counterstop 86 on the main frame of the machine is in idle position, stops 18 will freely pass it whether stops 18 are set or unset. When counterstop 86 is in active position all unset ones of the stops 18 will pass it but no set stop 18 will pass it. The projections 23 of set stops 18 will collide sidewise with the active or set counterstop 86 in successive tabulating jumps or runs of the carriage.

In key set tabulating mechanism for typewriting machines a different column stop is provided for each letter space position of the platen carriage and it is the common practice to have the set of column stops carried by a stop bar having a pair of opposed slots for each column stop. It has been found that the impact force against any one of these column stops in arresting a tabulating jump of the carriage frequently results in bending or breaking of teeth of the stop bar, this being particularly true in machines having fonts of types of the smaller type sizes and very short letter space movements. This difficulty is overcome by the present invention.

Two illustrative embodiments of the invention are shown in the drawing, namely, that shown in Figs. 1 to 8 and that shown in Figs. 9 to 11. In each construction there are as many column stops 18 as there are letter space positions of the carriage 10, i. e., if the carriage (for example) has a length of travel of 90 letter spaces there are 90 of the column stops 18. In the prior key set tabulating mechanisms referred to there would be required for such a 90 letter space carriage feed 90 slots 16 and 90 slots 17, involving (especially in machines having the shorter lengths of letter space feed movements) very close spacing of the slots 16 and a corre-

spondingly close spacing of the slots 17 with resultant thin and weak "teeth" or projections of the bar 14 between the slots of each row of slots 16 and each row of slots 17 in said bar 14. The present invention provides a coarser slotted or "toothed" stop bar with strong "teeth" while maintaining the important requirement of one column stop for each letter space and the ability to set any selected one or plurality of said column stops for coaction with the counterstop to stop the carriage in tabulating at any selected series of column stop positions (or letter space positions) of the carriage.

While according to the invention there are as many of the column stops 18 as there are letter space positions of the carriage, the stop bar 14 has a lesser number of the pairs of opposed slots 16-17 than there are stops 18 and there is engaged in each pair of opposed slots 16-17 a plurality of the stops 18, yet each stop 18 is adapted when set to coact with the usual counterstop (such as 86) to arrest the carriage in a different one of its letter space positions, and the carriage can be arrested in tabulating at any letter space position or series of said positions.

In the embodiment of the invention shown in Figs. 1 to 8 there are just half as many pairs of opposed slots 16-17 as there are column stops 18 or possible letter space positions of the carriage, and a group of two of the stops 18 is engaged in each pair of opposed slots 16-17. By this arrangement the spacing between the slots of the row of slots 16 and the spacing between the slots of the row of slots 17 is substantially doubled thus making the "teeth" or projections of the stop bar between the slots substantially twice as strong as in prior constructions such as above described.

In the modified embodiment of the invention shown in Figs. 9 to 11, the number of slots 16 and the number of slots 17 (or the number of pairs of opposed slots 16-17) is only one-third of the number of column stops 18 (or possible letter space positions of the carriage), and there is engaged in each pair of opposed slots 16-17 a group of three of the stops 18. By this modified arrangement the spacing between the slots of each row of slots 16 and the slots of each row of slots 17 is substantially tripled thus substantially tripling the thickness and strength of the "teeth" or projections on the stop bar 14 which define the slots of said rows of slots.

In order that the stops 18 may be set, in the embodiment shown in Figs. 1 to 8, for stopping the carriage at any selected letter space positions of the carriage, the projections 22 and 23 of the left hand stop 18 of each pair or group of stops 18 engaged in each single pair of opposed slots 16-17 are offset laterally or sidewise to the left of the main body portion of the stop substantially one-half a letter space distance of travel of the carriage, and the projections 22 and 23 of the right hand stop 18 of each said pair or group of stops are offset laterally or sidewise to the right of the main body portion of the stop substantially one-half a letter space distance of travel of the carriage. In other words, the projections 22 of the entire set of stops 18 are spaced one letter space apart longitudinally of the bar, and the same is true of the projections 23 of the entire set of stops 18. The slots 16 and slots 17 are each made just wide enough to loosely receive a group of two of the thin stops 18 with the main body portions

of said two stops abutting face to face and pivoted on wire 19.

In order that the stops 18 may be set, in the embodiment of the invention shown in Figs. 9 to 11, for stopping the carriage at any selected letter space positions of the carriage, the projections 22 and 23 of the central stop 18 of each group of three stops lie in the same plane as the main body portion of the stop, while the projection 22 and 23 of the left hand stop of each group are offset to the left substantially one letter space distance and those of the right hand stop are offset to the right substantially one letter space distance, all the projections 22 of all stops of the entire set of stops 18 in the modified construction being spaced apart one letter space and the same being true of all the projections 23 of all stops of said set. In Figs. 9 to 11 each slot 16 and 17 is made just wide enough to receive loosely the body portions of a group of three facewisely abutted thin stops 18 pivoted on wire 19.

In both forms of the invention shown slots 16 are uniformly spaced and slots 17 are given precisely the same spacing and width as slots 16, a slot 17 being directly opposed to each slot 16. For a carriage with a possible travel of 90 letter spaces, for example, there would be 90 stops 18 in each embodiment of the invention but only 45 slots 16 and 45 slots 17 in the embodiment of Figs. 1 to 8, and only 30 slots 16 and 30 slots 17 in the embodiment shown in Figs. 9 to 11.

In both forms of the invention each of those stops 18 whose projections 22 and 23 are offset laterally as above described has its projection 22 integrally joined to the main body of the stop by a stop portion 18^b and its projection 23 integrally joined to the main body of the stop by a stop portion 18^c. In the embodiment of the invention shown in Figs. 1 to 8 the spacing between the centers of the slots 16 longitudinally of the stop bar 14, and also the like spacing of slots 17, is substantially equal to two letter spaces, and in the embodiment shown in Figs. 9 to 11 said spacing is substantially equal to three letter spaces.

What I claim is:

1. In a tabulating mechanism for controlling tabulating movements of the platen carriage of a typewriter or like machine to arrest the carriage at selected letter space positions of the carriage, the combination of a set of column stops, one for each letter space position of the carriage, means supporting the column stops for selective setting and unset setting movements of the column stops, counter stop means for coaction with set ones only of the column stops, said column stop supporting means supporting the column stops in a series of spaced groups each consisting of a like number of column stops abutted face to face, and each column stop having an abutment portion which is positioned, by setting the stop, for coaction therewith of the counterstop means, the said abutment portions of the set of column stops being spaced a letter space distance apart along the path of travel of the carriage.

2. In a tabulating mechanism, the combination of a set of tabulating stops, and stop supporting means having a row of slots in which said stops are shiftable transversely of said row of slots to set and unset positions, each slot of said row having a plurality of said stops shiftable engaged therein, each stop of said set of stops having an abutment portion for coaction therewith of counterstop means in the set position of the stop, the abutment portions of the set of stops being

uniformly spaced apart longitudinally of the row of slots.

3. In a tabulating mechanism for typewriting or like machines having a traveling platen carriage, the combination of a transversely slotted column stop bar, and a set of column stops pivotally held to said bar in groups for setting and unsetting pivotal movements of each stop independently of the others transversely of the bar with each group of stops engaged in a different slot of said bar, each column stop having a contact portion for coaction with a counterstop for arresting the carriage, the contact portions of all stops of the set being uniformly spaced apart longitudinally of the column stop bar.

4. A key-set tabulating mechanism for controlling tabulating movement of the platen carriage of a typewriting machine, including a series of key settable and unsettable column stops individually settable and unsettable and equal in number to the number of letter space positions of the platen carriage of the machine, characterized in that the stops are confined in groups between teeth of a column stop bar which are spaced apart and are thick longitudinally of the path of travel of the carriage and are less in number than the number of stops, the stops of each group having body portions abutting face to face and being edgewise thin longitudinally of the path of travel of the carriage, each stop of the entire series of stops having an abutment portion for coacting with a suitable counterstop, the spacing apart of the abutment portions of the series of stops longitudinally of the path of travel of the carriage corresponding to the extent of a letter space movement of the carriage.

5. A key-set tabulating mechanism for typewriting machines as claimed in claim 4, wherein the column stops are pivotally mounted for edgewise rocking thereof individually transversely of the column stop bar for selective setting and unsetting of the stops.

6. A key-set tabulating mechanism for typewriting machines as claimed in claim 4, wherein the column stops are pivotally mounted for edgewise rocking thereof individually transversely of the column stop bar and of the path of travel of the carriage and for individual detachment and attachment of the stops.

7. In a tabulating mechanism for typewriting or like machines, the combination of a stop carrying bar having two parallel rows of transverse slots at opposite faces thereof, and a series of column stops each straddling said bar, the stops arranged in groups with each stop of the same group engaged in one slot of each of said two rows of slots and in the same slot of each row, each stop having an abutment portion for coaction with a suitable counterstop, the spacing apart of the abutment portions of the entire series of stops being uniform.

8. In a tabulating mechanism for typewriting or like machines, the combination of a set of column stops having flat body portions, and column stop supporting means including a column stop bar having a longitudinal row of transversely extending slots uniformly spaced along said bar and each equal in width to the thickness of two of said stops, said set of stops being mounted on said supporting means in groups of two facewisely abutted stops with each group of stops engaged in a different one of said uniformly spaced slots in said bar, the stops each

having a laterally offset abutment portion, the several abutment portions of the set of stops being uniformly spaced apart longitudinally of the bar, the abutment portions of the two stops of each of said groups of stops being laterally offset in opposite directions from the main body portions of the stops longitudinally of the bar.

9. In a tabulating mechanism for typewriting or like machines, the combination of a set of column stops having flat body portions, and column stop supporting means including a column stop bar having extending longitudinally thereof a row of transversely extending slots uniformly spaced apart along said bar and equal in number to one-third of the number of stops in said set of stops, each slot equaling in width longitudinally of the bar the thickness of a group of three of said stops, said set of stops being mounted on said supporting means in groups of three facewisely abutted stops with each of said groups of stops engaged in a different one of said slots in said bar, each stop having an abutment portion for coaction with a suitable counterstop, the abutment portions of the set of stops being uniformly spaced apart longitudinally of said bar, the abutment portion of the central stop of each group lying in the plane of the body portion of the stop, and the abutment portions of the two outer stops of each group being oppositely offset laterally of said stops.

10. In a key-set tabulating mechanism for controlling movements of the platen carriage of typewriting or like machines having a set of column stops and a stop setting and unsetting means coactive with any selected one of said column stops to individually set or unset the same, the combination with said set of column stops, of means supporting said set of column stops for setting and unsetting movements of each stop independently of the others, said supporting means including a bar extending longitudinally of the set of stops and having extending therealong a row of uniformly spaced slots each of which extends transversely of the bar, the number of said stops being a given multiple of the number of said slots, each slot being wide enough longitudinally of the bar to receive a number of said stops corresponding to said given multiple of the number of slots, each stop having two projections engageable by said setting and unsetting means to respectively set and unset the stop, one of said projections being adapted to serve also as an abutment for coaction with a counterstop to arrest tabulating movements of the carriage of the machine, the spacing apart of the said stop projections longitudinally of the bar being uniform throughout the set of stops.

11. In a key-set tabulating mechanism as claimed in claim 10, a set of said column stops each of which consists of a single piece of sheet metal, is inherently resiliently expansible and contractible, is individually releasably self-held to the supporting means for separate attachment and detachment, and is individually automatically releasably self-latchable to said supporting means in both the set and unset positions of the stop.

12. In a key-set tabulating mechanism as claimed in claim 10, a universal unsetting means for the stops simultaneously operable upon all set stops to unset the same.

13. In a typewriting machine having a key-set tabulating mechanism for controlling tabulating movements of the platen carriage of the machine, the combination of a set of column

stops, one stop for each letter space position of the carriage of the machine, means supporting said set of stops in spaced apart groups of stops for edgewise shifting of any stop of the set independently of the others transversely of the path of travel of the carriage to set and unset the selected stop, and a device for individually setting and unsetting any selected one of the stops, each stop having two spaced edge portions respectively engageable by said individual setting and unsetting device in a letter space position of the carriage peculiar to said stop to set and unset the stop, and each stop also having an abutment side face portion for coaction with a suitable counterstop to arrest a tabulating movement of the carriage in a letter space position peculiar to said stop, the said abutment side face portions of the stops of said set having a uniform spacing in the direction of travel of the carriage equal to one letter space distance of travel of the carriage.

14. A typewriting or like machine having a platen carriage mounted for travel back and forth, and a key set tabulating mechanism comprising a set of individually settable and unsettable column stops, stop supporting means carrying the stops of said set of column stops with the stops of said set arranged in spaced groups of two or more facewisely abutting stops, and abutments carried by the supporting means at opposite sides of each group of facewisely abutting column stops to resist facewise movements of the stops of the group relatively to said supporting means, each stop of the set of column stops having a side face portion for coaction with a counterstop means to arrest tabulating jumps of the carriage, and said side face por-

tions of the column stops being spaced apart uniformly along the path of travel of the carriage.

15. A typewriting machine as claimed in claim 14, characterized in that the stops are of arched form in side view and are edgewise resiliently expansible and contractible to releasably and shiftably grip the supporting means, whereby the stops are individually releasably self-held to the stop supporting means and are releasably self-latchable to said means in their set and unset positions.

16. In a tabulating mechanism for typewriting or like machines having a traveling platen carriage, the combination of a column stop bar having extending longitudinally thereof two parallel rows of slots on opposite faces thereof, each slot extending transversely of the bar, and a set of column stops each of which is pivotally held for pivotal setting and unsetting movements thereof transversely of the bar independently of the others about an axis extending longitudinally of the bar, the number of slots of each row being less than the number of stops of said set of stops, the set of stops being arranged in groups with the stops of each group pivotally engaged in one slot of a pair of slots and slidably engaged in the coincident slot of said pair of slots on the opposite face of said bar, the side walls of each pair of slots restraining the group of stops engaged therein from movement longitudinally of the bar, and each stop having a portion for contact with a counterstop for arresting the platen carriage, the said contact portions of the stops of all the groups of stops 35 having a uniform spacing along the stop bar.
